UNITED STATES PATENT OFFICE.

HIRAM C. STALLINGS, OF CARROLLTON, GEORGIA

SECURITY CASE.

Application filed November 22, 1922. Serial No. 602,584.

To all whom it may concern:

Be it known that I, HIRAM C. STALLINGS, a citizen of the United States, residing at Carrollton, in the county of Carroll and State of Georgia, have invented certain new and useful Improvements in Security Cases, of which the following is a specification.

This invention relates to cases for keys and the like, and more particularly to a 10 pocket key case.

One important object of the invention is to provide an improved construction of key case whereby a large number of keys may be carried and handled more conveniently 15 than with the present case.

A second important object of the invention is to provide an improved form of key case wherein the keys will be more safely kept than in the usual form and wherein 20 proper access to any particular key may be instantly had.

A third important object of the invention is to provide an improved form of key hook for use in connection with such a case.

A fourth important object of the invention is to provide an improved form of key case especially arranged to carry a large 25 number of keys which are held firmly in place when not in use, but which are readily accessible for instant use.

With the above and other objects in view as will be hereinafter apparent, the invention consists in general of certain novel details of construction and combinations of 35 parts hereinafter fully described, illustrated in the accompanying drawings and specifically claimed.

In the accompanying drawings like characters of reference indicate like parts in the 40 several views, and

Fig. 1 is a face view of the case open.

Fig. 2 is a section on the line 2—2 of Figure 1.

Fig. 3 is a detail view of the key hook plate and its attached parts, the form being slightly modified from that shown in Figure 1.

In the embodiments of the invention herein illustrated, there is shown a case consisting of a back portion 10 and flaps 11 and 12, which are preferably formed of leather or other suitable material. These flaps are connected to the back of flexible portions 13, and on one flap is provided a snap button 14, while the other flap carries a co-operating snap button 15.

The key holding plate proper consists of a flat plate 16 of Monel metal, this being used because of its peculiar wearing qualities and freedom from rust and corrosion. At the upper edge of this flat plate is provided a plurality of hinge members 17, and the plate is secured in position with these hinges substantially in alignment with the top of the back 10 by means of rivets 18. Secured to each of the hinge portions of the plate is a swinging plate 19, the free edge of which is rolled as at 20, and provided with slots 21, extending through the roll portion. Through the roll portion 20 passes a pin 22, and on this pin are secured the swinging hooks 23, each of which is provided with a straight shank portion, and a circular bill or key engaging portion 24, the end of this bill being positioned adjacent the shank portion as at 25, and turned slightly up to permit ready engagement of a hook. By reason of this 360 degree curve in the bill, the keys attached thereto swing readily and without jamming. Moreover, the plates themselves swing freely outward for movement of one or another set of keys outward together while the individual hooks are independently movable. Between the plates 19, it is preferred to place a single hook 26, which may be used for an automobile ignition lock key or other like key, and by means of this construction, the key attached to the hook 26 may be left outside of the case, while the remaining keys are kept within said case.

In the form shown in Fig. 3, there is provided in addition to the hook 26, a keeper loop 27, this being also provided in the form in Fig. 1 where the hook 26 is omitted. The purpose of this keeper loop is for the attachment of a key chain so that the user may have the case securely attached to his person.

In use it will be observed that anyone of the keys or bunches of keys carried on a single hook may be swung outward, or all of the keys or bunches of keys attached to the hooks of a single plate 19 may be similarly swung outward. Thus certain keys may be moved out, and the case closed, on the remaining keys. Moreover, the provision of the swinging plates carrying swinging hooks renders the attachment of the keys to the case very flexible, and makes it easy to select a desired key and use the same. It is to be observed that the metallic construction throughout is to be made of

the Monel metal, since this metal has been found to be the best adapted for the purpose, but other metals may be used if desired.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a key case of the class described, a base plate, swinging plates hinged to one edge of the base plate, swinging hooks hinged to the free edge of each plate and a further hook pivoted directly to the base plate.
2. In a key case of the class described, a base plate having a plurality of hinge members on one edge, a plurality of swinging plates secured to said hinge edge of the base plates for pivotal movement relative thereto, a plurality of hooks pivotally connected to the free edge of each plate and a further hook pivoted directly to the base plate.
3. In a key case of the class described, a base plate having spaced hinge portions along one edge, swinging plates each hinged to one of said portions, said plates being arranged in spaced relation to each other, a

key hook pivoted to the hinge edge of the base plate between the swinging plates, and other key hooks pivoted to the free edges of the swinging plates.

4. In a key case of the class described, a base plate having hinge portions arranged in spaced relation along one edge, swinging plates secured to said hinge portions in spaced relation to each other, said plates having their free edges formed to constitute tubular members, said members being slotted at intervals of their length, pins each passing through one of the tubular members, key hooks swingingly mounted on said pins in said slots, and an independent key hook pivotally mounted on the hinged edge of the main plate between the swinging plates.

5. In a key case of the class described, a base plate having hinge portions arranged in spaced relation along one edge, swinging plates secured to said hinge portions in spaced relation to each other, said plates having their free edges formed to constitute tubular members, said members being slotted at intervals of their length, pins each passing through one of the tubular members, key hooks swingingly mounted on said pins in said slots, an independent key hook pivotally mounted on the hinged edge of the main plate between the swinging plates, and a keeper loop also pivotally mounted on the main plate between the hinge plates.

In testimony whereof I affix my signature.

HIRAM C. STALLINGS.
